UNITED STATES PATENT OFFICE.

GEORGE B. KELLEY, OF ROCKFORD, ILLINOIS, ASSIGNOR TO THE JEWELERS CROWN GUILD.

DESIGN FOR A SPOON.

SPECIFICATION forming part of Design No. 22,228, dated February 21, 1893.

Application filed January 24, 1893. Serial No. 459,602. Term of patent 7 years.

To all whom it may concern:

Be it known that I, GEORGE B. KELLEY, of Rockford, in the county of Winnebago and State of Illinois, have invented a new Design for Spoons, &c.; and I do hereby declare the following, when taken in connection with accompanying drawings and the letters of reference marked thereon, to be a full, clear, and exact description of the same, and which said drawings constitute part of this specification, and represent, in—

Figure 1, a face view of the spoon; Fig. 2, a reverse view thereof.

My invention relates to a design for spoons &c., and consists in the configuration and ornamentation as herein shown and described.

The upper face of the spoon-handle bears a crown A, scrolls B, and leaf-forms C, two of

the scrolls being arranged opposite each other, to inclose a small, irregular shield D. The 20 back of the spoon-handle bears scrolls E, and leaf-forms F, which are arranged at the outer end of the handle to inclose a plain surface or shield G, of irregular outline.

Having fully described my invention, what 25 I claim is—

The design for spoons &c., as herein shown and described.

In testimony whereof I have signed this specification in the presence of two subscribing witnesses.

GEORGE B. KELLEY.
